UNITED STATES PATENT OFFICE

121,871

DESIGN FOR A COMBINED ADVERTISING DISPLAY STAND AND BOTTLES

William Hinkel, Milwaukee, Wis., assignor to Jos.
Schlitz Brewing Company, Milwaukee, Wis., a corporation of Wisconsin

Application April 20, 1940, Serial No. 91,820

Term of patent 7 years

To all whom it may concern:

Be it known, that I, William Hinkel, a citizen of the United States, residing at Milwaukee, in the county of Milwaukee and State of Wisconsin, have invented a new, original and ornamental Design for a Combined Advertising Display Stand and Bottles, of which the following is a specification, reference being had to the accompanying drawing, forming part thereof.

bined advertising display stand and bottles embodying my new design; and Figure 2 is a side elevational view thereof.

I claim:

The ornamental design for a combined advertising display stand and bottles, as shown.

WILLIAM HINKEL.
